COIN CONTROLLED GAME APPARATUS

Bon MacDougall, Los Angeles, Calif., assignor to
Fred C. McClellan, Chicago, Ill.

Application June 28, 1934, Serial No. 732,754

8 Claims. (Cl. 273—121)

This invention relates to certain novel improvements in a coin controlled game apparatus and has for its principal object the provision of an improved construction of this character which

5 will be economical in manufacture and which will provide the maximum degree of amusement.

Among the several objects of this invention is to provide a game apparatus comprising a combination and arrangement of parts which when 10 operated will simulate the playing of baseball.

A still further object of the invention is to provide a coin controlled amusement apparatus in which there is provided a diamond and an arrangement for progressively advancing a ball 15 or balls, simulating a base runner, along said diamond to a score receiving opening.

A still further object of the invention is the provision of a coin controlled game of skill in which there is provided a diamond and an arrangement for projecting a ball upon the diamond to be progressively moved around the diamond.

A still further object of this invention resides in the novel combination and arrangement of parts for automatically elevating a ball to a 25 playing surface and then automatically progressing the ball or balls over that playing surface.

Other objects will appear hereinafter.

The invention consists in the novel combination and arrangement of parts to be hereinafter 30 described and claimed.

The invention will be best understood by reference to the accompanying drawings, showing the preferred form of construction and in which:

Fig. 1 is a plan view of the coin controlled 35 game apparatus embodying my invention;

Fig. 2 is a sectional detail view of the same taken substantially on line 2—2 of Fig. 1;

Fig. 3 is a sectional detail view of the same taken substantially on line 3—3 of Fig. 2;

40 Fig. 4 is a fragmentary sectional detail view of a means embodied in the invention for progressively advancing a ball;

Fig. 5 is a fragmentary sectional perspective view of the ball progressing means embodied in 45 the invention;

Fig. 6 is a fragmentary sectional detail view of the automatic elevating means embodied in the invention; and

Fig. 7 is a plan view of the ball elevating means 50 with parts thereof broken away.

Referring more particularly to the drawings a game apparatus is indicated at 10. This game apparatus comprises a cabinet 11 having a glass top 12 beneath which is arranged a play board 13 having exit openings 14 formed therein. Beneath this play board 13 is a gate 15 having a plurality of openings 16 formed therein through which balls trapped in the exit openings 14 may pass when the gate 15 is shifted to dispose the 60 openings 16 into registration with the openings

14, the gate being adapted to support balls in certain of the openings 14 when the openings 16 are disposed from registration with the said openings.

The gate 15 is shifted through the medium of a coin controlled mechanism 17 of any approved type which includes the slide 18 having a coin aperture 19 formed therein, the inner end of the slide 18 being provided with an arm 20 having connection with the gate 15 to move the same for the purposes herein stated. This gate may be, though not necessarily, supported beneath the play board by suitable cleats 21 secured to adjacent walls of the cabinet 10 or in any suitable manner which will best serve the purpose.

Balls are projected through a ramp 22 by means of a suitable propelling mechanism 23 of a well known type including a plunger 24. From this ramp the balls are adapted to travel upon the play board and gravitate to the lower end thereof or after striking any one or more of the pins 23 disposed upon the play board 13 to pass through such of the openings 14 as are not obstructed by the gate 15, or be supported by the gate 15 in any of the other of the openings 14.

Beneath the gate 15 is a floor 24' and this floor 24' is provided with independent runways A and B. Each of these runways is provided with branch runways 25, and these branch runways as well as the runways 25', of which the branch runways 25 form a part, are adapted for communication with such of the openings 14 as are not, as stated herein, obstructed by the gate 15, said openings being indicated at 14'.

Disposed in the runway A in the path of balls which are adapted to travel therethrough are circuit breakers or switches 26 and 27 adapted to control an electric circuit between a source of electric energy 50 and electromagnetic devices or solenoids 29 hereinafter more fully referred to.

Formed upon the play board 13 is an object D simulating a diamond of a baseball field.

The corners 29' of this diamond simulate the bases thereof and at such corners there are formed in the play board 13, Fig. 4, openings 30 in which are movably positioned ball seats 31 in the form of inverted cuplike elements as shown.

Each ball seat 31 is pivotally connected to the play board 13 as at 36 in a manner such that when the gate 15 is in ball supporting position the gate will likewise support this ball seat in ball receiving position. But when the gate is moved from ball supporting position the ball seat will pivot downwardly, by gravity and discharge the ball upon the floor 24' for return to a trough 73.

Each ball seat is provided with a slot 76 to allow clearance for an arm 36, hereinafter referred to, when the seat drops to discharge a ball

therefrom, the return of the ball seat to ball supporting position being accomplished by movement of the gate 15 into ball supporting position.

Defining the diamond are parallel rail elements 32 between which are connecting runways 33 in the form of grooves formed in the surface of the play board 13 as shown in Fig. 5.

The solenoids 29 hereinbefore referred to are preferably connected in series as at S (Fig. 3) 10 and each includes a solenoid arm 34, the outer end of these arms 34 being angled upwardly through the corresponding slots 76 to provide the bat arms 36.

Each of the arms 34 is normally held in an outwardly projected position (full lines, Fig. 4) by means of a spring 37 one end of which is connected to the arm as at 38 and the other end of which is connected to the play board 13 as at 39.

Surrounding each of the openings 30 is a ring element 32' and these ring elements 32' function as ball stops so as to stop the played balls in the seat portions of the ball seats 31.

Provided by the floor 24' is a guideway 42 which is adapted to receive a ball from an opening 25 77 formed in the play board 13 and preferably designated as "batter-up" or a like designation.

This guideway at its lower end terminates in a slot 43 formed in the floor 24'.

Supported by the floor 24' as at 44 for pivotal 30 movement through this slot 43 is an arm 45 one end of which has associated therewith a ball receiving cup 46 adapted to receive a ball from the guideway 42 which in turn receives a ball which has passed through either of the openings 35 77 and 72, designated as "batter-up" and "single", respectively, Fig. 1.

The other end of the arm 45 is pivotally connected as at 47 to an arm 48 of a solenoid 49 which is connected in circuit with the source of 40 electric energy indicated at 50.

Formed in this ball receiving cup 46, Fig. 6, is an elongated slot 51. Projecting into this slot 51, when the cup 46 is in ball receiving position, is an operating cam 52 having one end portion 45 pivotally connected as at 53 to a fixed bracket 54. The other end of the operating cam is connected as at 54' to a link 57 which in turn is connected as at 58 to an arm 59, the latter being pivotally connected as at 60 to a fixed bracket 61. This 50 arm 60 is connected to one side of the source of electric energy 50 and has fixed thereon a contact head 55 adapted in a manner hereinafter explained to contact with a cooperating contact head 55' to complete the circuit between the solenoid 49 and the source of the electric energy 50. The arm 60 and cam 51 are normally held in the position shown in Fig. 6 by means of a spring member 62.

Adjacent the solenoid 49 is a bracket 63 the 60 upper end of which pivotally supports, as at 64, an L-shaped arm 65 one end of which is provided with a finger 66 adapted to engage the edge 67' of the operating cam 52 when disposed in the position shown in dotted lines in Fig. 6. The 65 other limb 67 of the L-shaped arm 65, at its end portion 68 provides a finger 69 adapted to engage the arm 45 when disposed in the position shown in dotted lines in Fig. 6.

The game apparatus insofar as it relates to my 70 present invention operates as follows: When a ball is projected from the ramp 22 upon the play board 13 and passes through the opening 77, it will drop into the runway 42 and gravitate into the ball receiving cup 46 whereupon the ball by virtue of its weight will pivot the operating cam

52 and link 57 in a downward direction to bring the contact head 55 into engagement with the stationary contact head 55' whereupon the circuit between the source of electric energy 50 and the solenoid 49 will be completed. When this takes place the solenoid 49 will operate to pivot the arm 45 upwardly to bring the ball receiving cup 46 into position to discharge the ball indicated at P upon the playboard for movement through the guideway 70 into the corner "E" of the diamond upon the ball seat 31 at that corner, which corner represents "home plate".

At the entrance of this corner is a pivotally supported gate 78 (Fig. 2) which will pivot upwardly by action of the ball "P" to allow the ball "P" to pass upon the ball seat but which will function, when the first ball "P" has not been advanced to first base, to direct a second ball through a runway 79 for passage through a ball return opening 80 which communicates with a return trough 73 by which the played balls are returned to a point adjacent the elevating device 74.

Assuming that the next ball projected upon the play board 13 from the ramp 22 passes through the one base opening indicated at 72, this ball will find entrance into the runway 42 whereupon it will gravitate therewith and into the ball receiving cup 46 where it will be elevated to the diamond in the manner hereinbefore recited in reference to the ball "P". If a ball passes through the opening indicated at 81 and designated as "two base", or through either of the openings 82 or 83 designated respectively as "three base" and "home run", the ball at the batter's box "E" will be progressed around the diamond according to the 110 number of base hits indicated at the opening through which the ball has passed. For example, if it be assumed that the third ball will pass through the opening 83 indicated as "home run", this ball will enter into the runway "B" and contact switches 28', 29', 30' and 31' arranged in the runway "B", completing a circuit between the corresponding solenoids 29 and the source of electric energy 50, thereby energizing the solenoids and causing the latter to operate successively the 115 four ball-advancing arms or fingers 36 to advance the ball from the batter's box "E" along the grooves 33 which describe the baseball diamond "D", the played balls passing from the diamond "D" through a runway 76' into an elongated opening 75' designating "runs", and in which opening the balls are releasably supported by the gate 15.

The balls from the runways "A" and "B" will gravitate, after having operated the respective switches of these runways to the return trough 73 where they will be returned by suitable elevating mechanism diagrammatically indicated at 74 to ball projecting position to be again projected by the projecting device 23, at the proper time, upon the play board 13.

A ball passing through either of the openings 84, designated "sacrifice hit", will drop into the corresponding one of the runways "A" and "B" and operate the switches therein (Fig. 3) to advance a ball or balls one base.

From the description herein it will be seen that the advancing of the balls around the diamond, simulating a baseball diamond, is automatic in character and that by action of the balls the balls are automatically elevated to the pitcher's box of the diamond for gravitation down to the batter's box where the ball or balls are automatically progressed along the diamond by the action of other balls projected upon the play board.

Such balls as do not pass through the openings 150

- hereinbefore referred to will either gravitate to one of the "out" openings indicated at 75 or to one of the "strike" or "ball" openings indicated at 85 and be held therein until the gate 15 is moved to discharge such balls therethrough.
- 5 While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.
- 10 Having thus described my invention what I claim as new and desire to protect by Letters Patent is:
1. A game apparatus comprising an inclined board upon which balls are adapted to gravitate and said board being provided with an object simulating a baseball diamond and said board having exit openings through which balls are adapted to pass to a point below said board; means operably controlled by balls passing through the exit openings of said playboard for elevating balls from a point below said board to a predetermined point upon said diamond; and means for progressively moving the balls around said diamond.
- 15 2. A game apparatus comprising an inclined board upon which balls are adapted to gravitate and said board being provided with an object simulating a baseball diamond, having openings at the corners thereof, movable ball seats in said openings, said board having exit openings through which balls are adapted to pass to a point below said board; means operably controlled by balls passing through the exit openings of said playboard for elevating a ball from a point below said board to a predetermined point upon said diamond; for gravitation to one of said ball seats; means for progressively moving said balls from said seats around said diamond, said play board being provided with an opening to receive the balls from said diamond, and means for releasably retaining said balls in said opening and for supporting said ball seats in ball receiving position.
- 20 3. A game apparatus comprising an inclined board upon which balls are adapted to gravitate and said board being provided with an object simulating a baseball diamond, said board having exit openings through which balls are adapted to pass to a point below said board; means operably controlled by balls passing through the exit openings of said play board for elevating balls from a point below said board to a predetermined point upon said diamond; and ball controlled means for progressively advancing the balls along said diamond.
- 25 4. A game apparatus comprising an inclined board upon which balls are adapted to gravitate and said board being provided with an object simulating a baseball diamond, said board having exit openings through which balls are adapted to pass to a point below said board; means operably controlled by balls passing through the exit openings of said play board for elevating balls from a point below said board to a predetermined point upon said diamond; said play board being provided with an opening to receive the balls from said diamond, and means for releasably retaining said balls in said opening and for supporting said ball seats in ball receiving position.
- 30 5. A game apparatus comprising an inclined board having a plurality of exit openings formed therein, means beneath the board for releasably retaining the balls in certain of said openings, a ball receiving element pivotally supported beneath the board and adapted for movement through an opening formed in said board to discharge a ball upon said play board, means for directing balls passing through certain of the exit openings to said ball receiving element, means for pivotally moving said ball receiving element into said ball discharging position, and means controlled by a ball to be elevated by said ball receiving element for operating said ball receiving element moving means.
- 35 6. A game apparatus comprising an inclined board having a plurality of exit openings formed therein, means beneath the board for releasably retaining the balls in certain of said openings, a ball receiving element pivotally supported beneath the board and adapted for movement through an opening formed in said board to discharge a ball upon said play board, means for directing balls passing through certain of the exit openings to said ball receiving element, means for pivotally moving said ball receiving element into said ball discharging position, and means controlled by a ball to be elevated by said ball receiving element for operating said ball receiving element moving means, said ball receiving element moving means including an electrically operated solenoid.
- 40 7. A game apparatus comprising an inclined play board having an object simulating a baseball diamond, electrically operated means for elevating a ball from a point below said board into a position to gravitate to a predetermined point upon said diamond, electrically operated means for progressively advancing said ball about said diamond, said board having an opening adapted to receive the balls from said diamond, and means slidably arranged beneath the board for releasably retaining the balls in said opening.
- 45 8. A game apparatus including an inclined board having exit openings formed therein, and having an object on the surface thereof simulating a baseball diamond, means for propelling balls for gravitation upon said board, a floor beneath said board, runways provided by said floor to receive balls from certain of said exit openings, a pivotally supported ball receiving cup beneath said board and adapted to receive the balls from one of said runways, electrically operated means for moving said ball receiving cup through an opening formed in the board to discharge a ball upon said diamond, means associated with said cup and actuated by a ball received thereby for controlling an electric circuit to said electrically operated means, electrically operated means for progressively moving balls around said diamond, and means disposed in the path of the other of the runways and adapted for engagement by balls traveling through said other runways for controlling an electric circuit to said second named electrically operated means.
- 50 9. A game apparatus comprising an inclined board having a plurality of exit openings formed therein, means beneath the board for releasably retaining the balls in certain of said openings, a ball receiving element pivotally supported beneath the board and adapted for movement through an opening formed in said board to discharge a ball upon said play board, means for directing balls passing through certain of the exit openings to said ball receiving element, means for pivotally moving said ball receiving element into said ball discharging position, and means controlled by a ball to be elevated by said ball receiving element for operating said ball receiving element moving means.
- 55 10. A game apparatus comprising an inclined board having a plurality of exit openings formed therein, means beneath the board for releasably retaining the balls in certain of said openings, a ball receiving element pivotally supported beneath the board and adapted for movement through an opening formed in said board to discharge a ball upon said play board, means for directing balls passing through certain of the exit openings to said ball receiving element, means for pivotally moving said ball receiving element into said ball discharging position, and means controlled by a ball to be elevated by said ball receiving element for operating said ball receiving element moving means.
- 60 11. A game apparatus comprising an inclined board having a plurality of exit openings formed therein, means beneath the board for releasably retaining the balls in certain of said openings, a ball receiving element pivotally supported beneath the board and adapted for movement through an opening formed in said board to discharge a ball upon said play board, means for directing balls passing through certain of the exit openings to said ball receiving element, means for pivotally moving said ball receiving element into said ball discharging position, and means controlled by a ball to be elevated by said ball receiving element for operating said ball receiving element moving means.
- 65 12. A game apparatus comprising an inclined board having a plurality of exit openings formed therein, means beneath the board for releasably retaining the balls in certain of said openings, a ball receiving element pivotally supported beneath the board and adapted for movement through an opening formed in said board to discharge a ball upon said play board, means for directing balls passing through certain of the exit openings to said ball receiving element, means for pivotally moving said ball receiving element into said ball discharging position, and means controlled by a ball to be elevated by said ball receiving element for operating said ball receiving element moving means.
- 70 13. A game apparatus comprising an inclined board having a plurality of exit openings formed therein, means beneath the board for releasably retaining the balls in certain of said openings, a ball receiving element pivotally supported beneath the board and adapted for movement through an opening formed in said board to discharge a ball upon said play board, means for directing balls passing through certain of the exit openings to said ball receiving element, means for pivotally moving said ball receiving element into said ball discharging position, and means controlled by a ball to be elevated by said ball receiving element for operating said ball receiving element moving means.

BON MACDOUGALL.
